UNITED STATES PATENT OFFICE.

ROBERT C. COLE, OF HARTFORD, CONNECTICUT, ASSIGNOR TO THE JOHNS-PRATT COMPANY, OF HARTFORD, CONNECTICUT, A CORPORATION OF CONNECTICUT.

ELECTRIC SWITCH.

1,159,361.

Specification of Letters Patent.

Patented Nov. 9, 1915.

Application filed July 15, 1914. Serial No. 851,087.

To all whom it may concern:

Be it known that I, ROBERT C. COLE, a citizen of the United States, residing at Hartford, in the county of Hartford and State of Connecticut, have invented a new and useful Improvement in Electric Switches, of which the following is a specification.

This invention relates to the class of electric switches that have all of the operating parts inclosed within a metal casing which prevents any malicious or inquisitive tampering with the circuits and also excludes gases so that any arc formed when the circuits are opened will not cause an explosion.

15 The object of the invention is to provide a switch of this character in which the stationary poles or wire terminals mounted in the base of the casing are connected or disconnected for closing and opening the circuit by means of inclosed electric fuses of the cartridge type that are carried by the cover of the casing and are forced into contact with the wire terminals by means of a rocker arm that is manipulated by a lever on 25 the outside of the casing. When the lever is turned in one direction the fuse terminals are, against the pull of springs, forced into contact with clips which form the wire terminals and when the lever is turned oppositely the springs are allowed to forcibly withdraw the fuse terminals from the clip terminals. The conducting parts are sealed in the casing so as to prevent explosion or tampering with the circuit but while thus 30 sealed the switch can be opened or closed at will, and when it is necessary to renew fuses opening the cover of the casing completely breaks the circuit so that the fuses may be handled without danger of short circuiting 35 any parts or accident to the attendant.

40

Figure 1 of the accompanying drawings shows a plan of the base of the casing which contains the clips that form the circuit wire terminals, and a view looking into the 45 opened cover of the casing and showing the inclosed fuses therein which act as the movable blades of the switch. Fig. 2 shows a vertical section with the casing shut and the switch closed. Fig. 3 shows a similar section with the switch open. Fig. 4 shows a side view of the casing. Fig. 5 is a section of the cover showing the posts by which the movable switch block is guided, also the arm, shaft and lever for closing the switch. 55 Figs. 6, 7 and 8 are detail views showing the

relations of the operating lever and the arm which closes the switch and allows it to be opened quickly, at different times.

The casing of this switch is desirably made of cast iron with a base section 1 and a cover section 2 that are desirably hinged together at one side by pintles 3. At the opposite side the parts may be secured together by the bolt 4 that is swiveled to the base and the nut 5 that turns on the bolt 60 against a part of the cover. A packing 6 is arranged around the edge of the cover so as to insure a tight joint when the casing is closed. Insulating bushings 7 are placed in the openings provided for the entrance of 65 the circuit wires.

Secured to the bottom inside of the base is an insulating block 8. This block is desirably made of porcelain and has insulating barriers 9 between the spring clips 10 of 70 conducting material which forms the circuit terminals. Connected with these terminal clips are binding collars 11 for the attachment of the ends of the circuit wires. The switch illustrated has six spring clips, three 75 acting as terminals for the service wires and three acting as terminals for the load wires of a three-wire system. Of course one set of terminals can be omitted if the device is to be used in a two-wire system.

80 Projecting downwardly from the top of the inside of the cover on each side near the middle are two posts 12. Movable up and down on these posts is a frame 13. Fastened across the under side of this frame near its 85 ends are two blocks of insulating material 14. Mounted on these blocks and projecting downwardly therefrom are fuse holding ears. The ears 15 have slots for receiving the terminals 16 at one end of the inclosed 90 fuses 17 and the ears 18 have slots controlled by spring latches 19 for receiving the terminals 20 at the other end of the inclosed fuses. The terminals of the fuses held by 95 these ears which are attached to the insulating blocks carried by the movable frame in the cover are in alignment with the spring clips which are mounted on the insulating block in the base and to which the ends of the circuit wires are fastened.

100 In the cover near the top and extending transversely is a shaft 21. This shaft passes through the cover and on the outside has a lever handle 22. Fixed on this shaft in the cover is a collar 23 with a lug 24. Loose on 105 110

the shaft adjacent to the collar is an arm 25 that has a lug 26 which is adapted to be engaged by the lug 24 on the collar 23 that is fixed to the shaft. The free end of the arm 5 bears a roll 27 which is adapted to engage the upper surface 28 of the middle of the frame which carries the fuses. This frame is normally held lifted by the spiral springs 29 of which there are desirably four. The 10 inner ends of the springs are connected with an eye 30 attached to the frame and their outer ends are connected with plugs 31 in the cover.

When the handle lever is thrown to one 15 side one edge of the lug 24 on the collar fastened to the shaft engages one edge of the lug 26 on the arm 25 that is loose on the shaft and this turns the arm so that the roll 27 will travel along the track 28 20 and force the frame down against the pull of the spiral springs and push the fuse terminals into the clips on the base, as shown in Fig. 2. When the handle is thrown over in the other direction the shaft turns freely 25 until the other edge of the lug 24 on the collar engages the other edge of the lug 26 on the arm and then the arm is moved back until after the roll passes the center at which time the springs draw up the 30 frame. This action is very quick for after the roll passes the center the arm is free to spring up away from the collar on the shaft. This carries the fuses to the position shown in Fig. 3.

35 These switches are especially serviceable for use in mines, mills and garages and for the starting and controlling of alternating motors. The circuit parts are completely armored and can be sealed tightly so that 40 no gas or explosive substance can get inside. The parts are also so protected that no one can tamper with the connections either out of curiosity or maliciousness, yet the switch can be operated in a proper manner by any 45 one. The fuses form the movable switch blades and these fuses can be easily and quickly placed in or removed from position for substituting live for dead fuses. Whenever the casing is opened for the substitution 50 of fuses the circuit will of necessity be open so that there can be no danger of accident.

The invention claimed is:

1. An electric switch having a casing 55 consisting of a base member and a cover member, an insulating block fixed in the base, conductor terminal clips mounted on the block, an insulating block supported by and movable in the cover, knife blade inclosed 60 fuses removably held by the block in the cover, the blades of said fuses being in alinement with the clips in the base, means for forcing the insulating block in the cover

toward the insulating block in the base and causing the engagement of the fuse blades 65 with the clips and locking them in such engagement, and springs which automatically retract the insulating block into the cover and withdraw the fuse blades from the terminal clips when said locking means is released. 70

2. An electric switch having a casing consisting of a base member and a cover member, an insulating block fixed in the base, terminal clips mounted on the block in the 75 base, an insulating block supported by and movable in the cover, fuse blade clips mounted on the block in the cover, knife blade inclosed fuses held by said fuse clips with their blades alined in a plane passing 80 through the clips on the block in the base, posts supported by the cover for guiding the movements of the fuse block, springs for retracting the fuse block into the cover, and means for forcing the fuse block down into 85 the base and holding it there against the pull of the springs.

3. An electric switch having a casing consisting of a base member and a cover member, an insulating block bearing terminal 90 clips fixed in the base, an insulating block carrying fuse clips supported by and movable in the cover, said fuse clips being alined in a plane passing through the terminal clips, posts for guiding the movable 95 block in the cover, springs for drawing the block into the cover, a shaft extending through the cover, a handle on the outside of the cover, and an arm turned by but having a limited movement on the shaft inside of 100 the cover, said arm being adapted to engage the fuse block and force it out of the cover and lock it against the pull of the springs when the handle is turned in one direction and when the handle is turned in the other 105 direction to release the block so that the springs will retract it.

4. An electric switch having a casing consisting of a base member and a cover member, insulated terminal clips fixed in the 110 base, a frame supported by and movable in the cover, knife blade inclosed fuses mounted on said movable frame in the cover with their blades in alinement with the clips in the base, means for moving the frame and causing the fuse blades in the cover to engage and be locked in contact with the clips in the base, and springs which automatically retract the frame and withdraw the fuse blades from the clips when said frame moving and locking means are released. 115
